CLAIM

The ornamental design for a flask for perfumery product, as shown and described.

DESCRIPTION

FIG. 1 is front view of a flask for perfumery product according to the present invention.

FIG. 2 is a right side view of the flask for perfumery product depicted in FIG. 1.

FIG. 3 is a left side view of the flask for perfumery product depicted in FIG. 1.

FIG. 4 is rear view of the flask for perfumery product depicted in FIG. 1.

FIG. 5 is a top view of the flask for perfumery product depicted in FIG. 1.

FIG. 6 is a bottom view of the flask for perfumery product depicted in FIG. 1; and,

FIG. 7 is a perspective front, top and right side view of the flask for perfumery product depicted in FIG. 1.
